DESIGN FOR A FRAME FOR PICTURES AND THE LIKE

Antonino Pacenzia, Buffalo, N. Y.

Application February 24, 1940, Serial No. 90,481

Term of patent 3½ years

To all whom it may concern:

Be it known that I, Antonino Pacenzia, a citizen of the United States, residing at Buffalo, in the county of Erie and State of New York, have invented a new, original, and ornamental Design for a Frame for Pictures and the like, of which the following is a specification, reference being had to the accompanying drawing, forming part thereof.

In the accompanying drawing:
Fig. 1 is a front elevation of a frame embodying my design.

Fig. 2 is a top plan view of the same.

I claim:

The ornamental design for a frame for pictures and the like, as shown.

ANTONINO PACENZIA.
